Primary Examiner — Cynthia R Underwood(74) *Attorney, Agent, or Firm* — Sanchelima & Associates, P.A.; Christian Sanchelima; Jesus Sanchelima(57) **CLAIM**

The ornamental design for cord organizer, as shown and described.

DESCRIPTION

FIG. 1 is an isometric view of a cord organizer showing my new design, in a closed configuration;

FIG. 2, is an isometric view in an open configuration;

FIG. 3 is a front elevational view thereof;

FIG. 4 is a rear elevational view thereof;

FIG. 5 is a left side elevational view thereof;

FIG. 6 is a right elevational view thereof;

FIG. 7 is a top plan view thereof; and,

FIG. 8 is a bottom plan view thereof.

The broken lines represent the charging cord, magnets and decorative ornaments and form no part of the claim.

1 Claim, 5 Drawing Sheets(56)
